UNITED STATES PATENT OFFICE

2,053,701

RACK

Riley H. Coons, Scotia, N. Y.

Application April 11, 1936, Serial No. 73,957

1 Claim. (Cl. 312—112)

The present invention relates to a rack designed particularly for holding milk bottle caps and has for its prime object to provide means whereby a plurality of series of milk bottle caps may be held in a convenient manner for ready use in the application of the cap to the bottle.

Another important object of the invention resides in the provision of an exceedingly simple and inexpensive structure of this nature which is 10 convenient in manipulation, inexpensive to manufacture, thoroughly efficient and reliable in use and operation, and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

20 In the drawings:—

Figure 1 is a front elevation of an apparatus embodying the features of my invention.

Figure 2 is a side elevation thereof.

Figure 3 is a vertical section therethrough taken 25 substantially on the line 3—3 of Figure 1.

Figure 4 is a sectional view taken substantially on the line 4—4 of Figure 2.

Figure 5 is a sectional view taken substantially on the line 5—5 of Figure 1.

30 Figure 6 is a detail elevation in perspective of one of the tubes showing a portion of the side wall thereof broken away.

Referring to the drawings in detail it will be seen that I devise an apparatus comprising a 35 rear wall 5 which merges at its upper edge into a front wall 6 which extends downwardly and diverges outwardly therefrom and has its side edges merging into side walls 7 of right triangular construction with the hypotenuse wall edges merging 40 into the edges of the front wall 6 and the right upstanding edges merging into the wall 5. The rear wall 5 is provided merging from its lower edge into a forwardly directed ledge or shelf 8. The wall 6 is provided with an oblong transverse 45 opening at the bottom end thereof with ledges or frame-work 9 with a transparent panel 10 therein. A plurality of indicia disclosing bottle caps 11 are disposed in this frame one adjacent each compartment as indicated to advantage in Figure

4 divided by division right triangular divisible walls 13. In each one of these compartments is a tube 14 containing a plurality of bottle tops 15 corresponding as far as the indicia is concerned to the bottle tops of the element 11. 5

From the above detailed description it will be seen that a tube 14 is mounted into the holder up through the bottom end thereof and then the lower end is switched over to the left, referring to Figure 3, so as to rest on the ledge or shelf 8 10 and the tops or caps therein correspond, of course, to the caps 11 in the frame 9. In this way it will be seen that it is easy to select the particular caps that may be desired or the like in a relatively small dairy wherein different grades of cream, 15 milk, and the like are being dispensed or sold.

It is thought that the construction, operation, utility and advantages of this invention will now be quite apparent to those skilled in this art without a more detailed description thereof. 20

The present embodiment of the invention has been described in considerable detail merely for the purposes of exemplification since in actual practice it attains the features of advantage enumerated as desirable in the statement of the invention and the above description. 25

It will be apparent that changes in the details of construction, and in the combination and arrangement of parts may be resorted to without departing from the spirit or scope of the invention as hereinafter claimed or sacrificing any of its advantages. 30

What is claimed is:—

An apparatus of the class described comprising a rear wall, a front wall secured at its upper edge 35 to the rear wall and inclining outwardly and downwardly therefrom, side walls connecting the side edges of the first two mentioned walls, vertical partitions providing a plurality of compartments, and a ledge or shelf projecting forwardly 40 from the bottom edge of the first mentioned wall at the lower end thereof toward the front wall, said shelf extending under each of the compartments and having its front edge spaced from the front wall to provide an opening through which 45 to insert articles upwardly between the walls for positioning on the shelf.
